SUSPENSION MEANS FOR VERTICAL SHAFTS

Filed Oct. 23, 1950

UNITED STATES PATENT OFFICE

2,626,120

SUSPENSION MEANS FOR VERTICAL SHAFTS

Frederick C. Baker, Portland, Oreg.

Application October 23, 1950, Serial No. 191,639

1 Claim. (Cl. 248—343)

1

This invention relates to means adapted to support a shaft flexibly in a desired relative position in such manner that when the shaft is temporarily moved out of such desired position, by application of a temporary force, it will be automatically returned to the desired position when relieved of the application of such force.

I believe the most important use for the invention will be found in its adaptation for the suspension of vertical shafts and the like to which lighting fixtures are secured, and consequently my invention relates particularly to means for flexibly suspending a vertical shaft for lighting fixtures, and the invention will be described with reference to this particular important use, although other applications of the invention are not to be considered as excluded.

When lighting fixtures are suspended from the ceiling it is desirable that they be allowed a certain amount of freedom to swing, for example in the event that something inadvertently strikes against them, thus reducing the likelihood of their being damaged by such contact. Also it is important that thereupon they return to their original proper position with their shafts, by which they are suspended, exactly vertical.

Furthermore, when the fixtures are square or rectangular in design, as in the case particularly of many modern design lighting fixtures, where certain lines of the fixture are intended to be parallel to, or at some fixed angularity with respect to, the walls or to the architectural or decorative lines in the ceiling, then it is also very desirable that when such fixtures are temporarily disturbed, even to the extent of receiving partial rotation, they return to rest again in exactly the desired parallelism or angularity intended. A common and well recognized difficulty with lighting fixtures of modern square design, having their shafts connected to ceiling mountings by customary types of universal joints, is that such fixtures in time, for one reason or another, become turned slightly, thus spoiling the general effect of such fixtures.

The particular object of the present invention accordingly is to provide an improved means for supporting a suspended vertical shaft which will permit a limited amount of universal swinging movement for the shaft but will cause the shaft always to return to rest in its original vertical position, and which will at the same time hold the shaft against any undesired partial and permanent rotation.

Another object of the present invention is to provide a permanent support for a shaft which

2

will maintain the shaft normally in exact axial alignment with an element in the support while temporarily permitting the movement of the shaft into a position of axial angularity with respect to such element.

A further object of the invention is to provide a new and useful shaft supporting or suspending means which will be practical, simple and inexpensive to manufacture.

10 The way in which the above mentioned objects and incidental advantages are attained, and the manner in which the invention may be employed for the special purpose of providing a suspension support for a lighting fixture shaft—such use being understood as a preferred embodiment of the invention—will be briefly described with reference to the accompanying drawings, in which:

20 Fig. 1 is a perspective view of a suspended lighting fixture in which my present invention is employed in the ceiling support for the upper end of the fixture shaft, the customary ceiling cap covering the support in the ceiling being omitted from the figure;

25 Fig. 2 is an elevation of the ceiling end of the fixture, drawn to a larger scale, with the ceiling cap in place;

30 Fig. 3 is a fragmentary vertical section taken through the center of the ceiling end of the fixture of Fig. 2, but drawn to a still larger scale;

35 Fig. 4 is an elevation of the ceiling support for the fixture with the ceiling cap removed;

40 Fig. 5 is a section on line 5—5 of Fig. 4, but showing the two cooperating elements of the shaft support moved apart axially for the sake of clarity.

Fig. 6 is an elevation of the two elements of Fig. 5 by themselves and in their same positions, a portion of the lower element shown broken away; and

45 Fig. 7 is a perspective view of the cooperating, specially formed, end of one of the two elements of Figs. 5 and 6, the ends of both elements being identical.

The present invention is closely related to the invention described in U. S. Letters Patent No. 2,470,282 issued under date of May 17, 1949, to Frederick C. Baker and Elbert Gary Spencer, entitled "Mounting for Shafts and the Like," and reference should be made to this prior patent for a clearer understanding of the present invention.

50 Referring to Figs. 1, 2 and 3 of the accompanying drawings, the lighting fixture, the main portion of which is indicated by the reference character 10 in Fig. 1, is illustrated as being of

special modern square-shaped design, in which the square contour lines are intended to be maintained in parallelism with the respective walls of the room.

The main portion 10 of the fixture is rigidly secured to the center vertical shaft 11 as usual, by which shaft the fixture is suspended at the desired distance below the ceiling 12, and through which the electric wires pass from the ceiling electric outlet to the light socket in the fixture.

The suspension support for the shaft 11, and the preferred form of my invention which is illustrated in the drawings, comprises two cooperating tubular members 13 and 14 (Figs. 3, 4, 5 and 6). These tubular members 13 and 14 preferably, though not necessarily, have the same corresponding diameters, in which case they can both be cut from the same piece of tubular shafting. It is necessary, however, when the support is made in the form shown in these figures, that the interior diameter of the lower member 13 be greater than the outside diameter of the fixture shaft 11, so that the latter will be able to swing to a limited extent in any direction within the lower member 13, the latter member being held stationary.

The tubular lower member 13 is stationary and is secured firmly to the ceiling, but is spaced a short distance below the ceiling as shown, being held by a pair of diametrically opposite brackets 15 and 15', the bottom ends of which are welded or otherwise rigidly attached to the lower member 13 and the upper ends of which have outwardly extending flanges provided with apertures for suitable screws for anchoring the brackets, and therewith the member 13, in place on the ceiling.

The upper end of the fixture shaft 11 is secured within the upper member 14 in any suitable manner. For example, a collar 16 is rigidly secured to the outside of the upper end of the fixture shaft 11 and rigidly secured within the upper member 14 as shown in Figs. 3 and 5.

The abutting or engaging ends of the members 13 and 14—thus the upper end of the lower member 13 and the lower end of the upper member 14—are identical and each end comprises a pair of identical diametrically opposite V-shaped grooves. The pair of V-shaped grooves of each member extends to the end of the member from diametrically opposite points on the exterior surface and meet at diametrically opposite points to 50 form two tips.

The exact manner in which the grooved engaging end of each member is formed can be best described with reference to Fig. 7. The two grooves 18, 19 and 18', 19' start from points 17 and 17' on the outside surface diametrically opposite each other and meet at points 29 and 29' which are diametrically opposite each other and turned 90° from the points 17, 17'. The two bottom or vertex lines 21 and 21' of the two grooves would, if continued forward, as indicated by the broken lines in Fig. 7, meet at a point 22 on the axis of the member, and similarly the two ridge lines 23 and 23', terminating at the outer points 29 and 29' respectively, would, if continued inwardly, also meet at the same point 22 on the axis of the member. The distance of each of the points 17, 17', 29, 29' from the center point 22 is equal, and the plane determined by the lines 29, 22 and 29', 22 is perpendicular to the plane determined by the lines 17, 22 and 17', 22, and both planes intersect along the axis of the member.

From this description of Fig. 7 it will be clear that the ends of the two members 13 and 14 are

cut in the same manner as the engaging ends of the shafts 14 and 15 in previously mentioned Patent No. 2,470,282. Not only does this forming of the abutting ends of the two members insure 5 perfect mating but it simplifies the cutting of the ends of the members.

Referring now particularly to Figs. 3 and 4, when the upper member 14 has been rigidly secured on the upper end of the fixture shaft 11, 10 with the axis of the upper member 14 in exact alignment with the axis of the shaft 11, the lower end of the shaft 11, before the fixture is fastened thereto, is inserted through the lower member 13. It will now be apparent that when the securing 15 brackets 15, 15' of the lower member 13 are fastened in place on the ceiling, with the axis of the lower member exactly vertical, the shaft 11 will be suspended in such manner that, while it may, if given a side thrust, swing to a limited 20 extent in any direction, it will always quickly return to its exact normal position. Furthermore, it cannot be rotated unless it can be raised sufficiently so that the upper member 14 will be entirely clear of the lower member 13, but, if this is 25 done, the shaft will always return to exact vertical position and, if rotated when so raised, will be turned exactly 180° or multiples thereof.

In assembling the fixture when the shaft 11 has been inserted through the lower member 13, the 30 shaft is inserted through the ceiling cap 24 (Figs. 2 and 3) and the main body portion 10 (Fig. 1) of the fixture is secured to the shaft 11. (Or the main body of the fixture 10 may be first secured to the shaft 11 and the ceiling cap 23 and lower member 13 slid over the upper end of the shaft before the upper end of the shaft is secured in the upper member 14.) Then the lower member 13 is mounted in place on the ceiling, the conductor wires extending through the shaft 11 being connected up to the outlet in the ceiling. Finally the ceiling cap 23 is secured in place in any suitable manner; for example, the ceiling cap may have a bottom collar 25 (Figs. 2 and 3) threaded on the inside and adapted to be screwed on the lower threaded end of the lower member 13, or the collar 25 may be secured to the lower member 13 by set screws.

I claim:

A suspension device for a lighting fixture and the like comprising a pair of tubular members having their external and internal diameters substantially equal respectively, an identically formed end on each member, each of said ends formed with a pair of identical, diametrically opposite, V-shaped grooves extending from diametrically opposite points on the outer surface of the member to diametrically opposite tip points on the outer surface at the end of the member, the bottom vertex lines of said grooves located in a plane with the axis of the member, the ridge lines at said tip points formed by the intersections of said grooves located in a plane with the axis of the member and perpendicular to said first mentioned plane, whereby said ends of said members will be capable of mating when brought together if said members are in axial alignment, means rigidly attached to one of said members and secured to a ceiling mounting, said means firmly holding said latter mentioned member at a spaced distance below said ceiling mounting with its axis vertical and its mating end uppermost, said latter mentioned member constituting the lower of said members in said device, the other member positioned above said lower mem-

ber with its mating end down and constituting the upper of said members in said device, a suspension shaft for the lighting fixture, said shaft extending upwardly through said lower member and having an external diameter considerably less than the internal diameter of said lower member, and means rigidly securing the upper end of said shaft to said upper member and in axial alignment with said upper member, whereby said shaft and therewith the lighting fixture will be supported by said upper member in turn resting on said lower member, and whereby said shaft may be given a limited swing in said device, and, when raised slightly, may be rotated, but, when released, will again become vertical and be either in original position or rotated exactly

180° or multiples thereof from such original position.

FREDERICK C. BAKER.
